UNITED STATES PATENT OFFICE.

JOHN RIGLING, OF PHILADELPHIA, PENNSYLVANIA.

DIRECT AIR DISPLACEMENT-PUMP.

1,289,543.

Specification of Letters Patent.

Patented Dec. 31, 1918.

Application filed July 30, 1918. Serial No. 247,441.

To all whom it may concern:

Be it known that I, JOHN RIGLING, citizen of the United States, residing at Philadelphia, in the county of Philadelphia and 5 State of Pennsylvania, have invented certain new and useful Improvements in Direct Air Displacement-Pumps, of which the following is a specification.

This invention relates to direct air displacement pumps, and belongs to that class of compressed air water elevators wherein the inlet and exhaust valve for controlling the air served to the pump chambers is operated by a rocking contrivance set in motion 15 without the employment of floats in the chambers and by means of the air.

This invention has for its object the production of rocking mechanism wherein a body of fluid mercury is shifted by a small 20 portion of compressed air, from one side to the other of a pivotal support, causing the parts containing the mercury to rock, and at the same time operating the valvular device by which the mercury container or 25 conduit is served the compressed air necessary to move the mercury as hereinafter explained.

The construction and arrangement of the parts of this invention are set forth in the 30 accompanying drawings, of which Figure 1 represents a front view of all parts assembled. Fig. 2 is a vertical cross-section of one of the pump chambers. Fig. 3 is a top plan view of the slide valve casing. Fig. 4 is a section lengthwise of the slide valve 35 and casing on the broken line 4—4 of Fig. 3. Fig. 5 is a cross-section of the slide valve and casing on the broken line 5—5 of Fig. 3. Fig. 6 is a front view, slightly enlarged, of the air and mercury conduits and hollow 40 terminals, partly in section. Fig. 7 is a vertical section of the air distributer or valvular device on the broken line 7—7 of Fig. 8. Fig. 8 is a cross-section of the air distributer 45 on the broken line 8—8 of Fig. 7.

Throughout the drawings and description the same numbers are employed to refer to the same parts.

Considering the drawings, the pump 50 chambers 1 and 2 have the discharge pipes 3 and 4 combined in an outlet 5, all of the customary construction. The pump chambers have connected with them the air pipes 6 and 7, which engage connections 8 and 9 5 of the slide valve casing 10. The slide valve, and the parts hereinafter described, are sup-

ported by a wall or base plate 11, and the slide valve is supplied with compressed air by the pipe 12 that engages the connection 13 of the slide valve casing. A slide valve 60 14 has the ordinary cavity 15 and covers in its movement the ports 16, 17 and 18. Ports 16 and 18 are those admitting air to the pump chambers, and port 17 permits the air to pass into the exhaust passage 17a. 65 Valve 14 slides upon the table or partition 19, and is moved by the rod 20 that passes out of the casing by way of the stuffing box 21. The slide valve is held to its seat by the pressure block or cage 22, upon which 70 pressure may be exerted by the screw 23 that extends upwardly through the top of the casing 10.

The valve rod 20 is worked in and out by a pivoted lever 24, which has a pin 25 75 sliding out and in a bore 26 in the lever. The lower end of the pin 25 is pivotally connected with the slide valve rod 20. The upper end of the lever 24 has a longitudinal bore 27 and pin 28 therein, similar in size, 80 shape and disposition to the parts 25 and 26 just described, and the pin 28 is pivotally connected with an ear 29 of the rocking portion or member 30 of the air distributer. As best shown in Fig. 7, the distributer 85 comprises the rocking external portion 30, having the annular flange or lip 31 projecting from its lower edge and engaging a corresponding recess in the rabbeted ring 32, by which the rocking portion 30 is mov- 90 ably held upon the support 33. The air distributer has also a stationary interior portion or core composed of the upper cylinder 34, and the lower cylinder 35, the upper cyl- 95 inder being held against rotation with respect to the lower by means of the connecting dowel pins 36 and 37. The rocking member is arranged concentrically with the station- 100 ary portion of the distributer. Compressed air may be supplied to the stationary por- 105 tion of the distributer by the air pipe 38 connected with the main air pipe 12, as illustrated in Fig. 1. The air enters a cavity 39 in the cylinder 34, and by way of ducts 40 and 41 the air may enter the tube 42, 105 the end of which is connected with the rock- 110 ing portion of the air distributer. The upper cylinder 34 of the stationary portion of the air distributer has a second duct similar to the duct 40, and at an angle therewith marked 43 and indicated in Fig. 6. This duct 43 may be brought to register with a

duct 44 in the rocking portion 30 similar to the duct 41 and directly opposite to it in position. In Fig. 7 the duct 44 is shown in communication with the exhaust duct 45 in the cylinder 34 and also with the exhaust port 46 formed through the top of the rocking portion 30 and registering with the exhaust duct 45. As shown in Figs. 1 and 6 the top of the rocking portion 30 is pierced by a second exhaust port 46^a of similar size, and the cylinder 34 has also a second exhaust duct similar to the duct 45, but not shown, arranged to register with the exhaust port 46^a. The duct 44 in the rocking portion 30 is shown in communication with the tube 47. The tubes usually occupy an inclined position as illustrated in Fig. 6, and it will be observed that the axes of those tubes pass through the center of the distributor. The outer end, and in Fig. 6 the lower end of the tube 42, is connected with the hollow, closed terminal receptacle 48, usually a hollow sphere, and the receptacle 48 carries a body of fluid mercury 49. The receptacle 48 is connected as shown with the tube 51, the inner end of which is connected with the rocking portion 30 of the distributor. Tubes 42 and 51 form one pair of tubes projecting upon one side of the rocking portion of the distributor. On the opposite side of the rocking portion, the spherical receptacle 50 connects the outer, and in Fig. 6 the upper ends of the tubes 47 and 52, which comprise the second pair of projecting tubes. It will be observed that the tubes 47 and 42 are higher in position than the tubes 51 and 52. The higher tubes are the air conduits and the lower tubes the mercury conduits in this invention. Passage 53 connects tubes 51, 52.

It is not intended to limit the size, length or forms of the tubes or the terminals joining their outer ends.

The tubes and terminals rock with the rocking portion 30, and the rocking movement is limited and adjusted in degree by means of the projecting stops 54 and 54^a carried by the rocking portion 30 of the distributor, which come into contact with the screws 55 and 56, best shown in Fig. 8.

In Fig. 1 it will be noted that the air pipe 38 has a valve 57, and the main air pipe a valve 58.

In Fig. 2 the water enters the pump chamber 2 by way of the check valve 59, and passes out into pipe 4 by way of the check valve 60, all of customary pattern and action.

By reason of the passage 53, formed in the rocking portion 30, and permanently connecting the mercury conduits or tubes 51 and 52, those tubes may be held to constitute a single mercury conduit, pivoted in the middle.

The operation of this invention may be

explained by assuming the parts to be in the positions shown. By way of the air pipe 38, cavity 39, and ducts 40 and 41, compressed air enters tube 42 and is delivered in receptacle 48 above the surface of the mercury 49. The mercury is forced up through the lower tubes 51 and 52, the air leaving the tubes and receptacle 50 by way of the higher tube 47, ducts 44, 45, and exhaust port 46. When sufficient mercury has reached the higher parts to overbalance the tubes, they rock and the receptacle 50 becomes in its turn the lower end of the rocking devices. As the tubes rock, the lever 24, shown in Fig. 1, and its sliding members move the valve rod 20 of the slide valve 14, and that valve is drawn to the left. This movement will allow the compressed air to enter pump chamber 2 and drive out its contained charge of water, and, at the same time permitting the charge of compressed air in chamber 1 to escape and the chamber to take in another body of water. It will be understood that by regulating the flow of air to the distributor by means of valve 57, the time of rocking change or movement of the tubes can be controlled, and the time is controlled in accordance with the pressure of the water entering the pump chambers, and in accord also with knowledge and experience gained in the use of pumps of this nature.

Having now described this invention and explained the mode of its operation, I claim:

1. In a direct air displacement pump, the combination with a pumping chamber, of air inlet and exhaust valve mechanism, means for operating the said mechanism comprising an air distributor having a rocking portion and a stationary portion, means for operatively connecting the said rocking portion of the distributor and the said valve mechanism, pairs of tubes, the inner ends of the tubes being connected with the said rocking portion of the distributor, one pair of tubes projecting from one side of the said rocking portion and the other pair of tubes projecting from the opposite side thereof, one tube of each pair of tubes being arranged lower than the other, hollow, closed, terminal receptacles, the outer ends of the tubes being connected with the said receptacles, the said rocking portion of the distributor having a passage connecting the said lower tubes of each pair of tubes, means for supplying compressed air to the said stationary portion of the distributor, the said portions of the distributor having ducts and exhaust ports whereby the higher tubes of the pairs of tubes are alternately placed in communication with the said air supply and exhaust ports, and a body of liquid mercury carried in the said tubes and terminals whereby air pressure in the higher tubes drives the mercury from the lower to

the higher terminal causing the distributor to rock.

2. In a direct air displacement pump, the combination with a pumping chamber, of air inlet and exhaust valve mechanism, means for operating the said mechanism comprising an air distributor having a rocking portion and a stationary portion, means for operatively connecting the said rocking portion of the distributor and the said valve mechanism, pairs of tubes, the said stationary portion of the distributor being cylindrical and the rocking portion being arranged concentrically with the stationary portion, pairs of tubes, the inner ends of the tubes being connected with the said rocking portion of the distributor, one pair of tubes projecting upon one side and the other pair of tubes projecting from the opposite side of the said rocking portion, one tube of each pair of tubes being arranged higher than the other and the axes of the said higher tubes being in the same line passing through the center of the distributor, hollow, closed, terminal receptacles, the outer ends of the said tubes being connected with the said receptacles, the rocking portion of the distributor having a passage connecting the lower tubes of each pair of tubes, means for supplying compressed air to the said stationary portion of the distributor, the said portions of the distributor having ducts and exhaust ports whereby the said higher tubes of the pairs of tubes are alternately placed in communication with the said air supply and exhaust ports, and a body of liquid mercury carried in the said tubes and terminals whereby air pressure in the said higher tubes drives the mercury from the lower to the higher terminal causing the rocking of the distributor.
3. In a direct air displacement pump, the combination with a pumping chamber, of air inlet and exhaust valve mechanism, means for operating the said mechanism comprising an air distributor having a rocking portion and a stationary portion, means for operatively connecting the said rocking portion of the distributor and said valve mechanism, pairs of tubes, the inner ends of the tubes being connected with the said rocking portion of the distributor, one pair of tubes projecting from one side and the other pair from the opposite side of the said rocking portion, one tube of each pair of tubes being arranged lower than the other, means for connecting the outer ends of the tubes of each pair whereby the tubes of each pair are in communication with each other at their outer ends, the said rocking portion of the distributor having a passage

connecting the said lower tubes of each pair of tubes, means for supplying compressed air to the said stationary portion of the distributor, the said portions of the distributor having ducts and exhaust ports whereby the said higher tubes of the pairs of tubes are alternately placed in communication with the said air supply and exhaust ports, and a body of liquid mercury carried in the said tubes whereby when the said tubes are in an inclined position the air pressure drives the mercury from the lower tube of the pair in the lower position into the lower tube of the pair in the higher position causing the distributor to rock.

4. In a direct air displacement pump, the combination with a pumping chamber, of air inlet and exhaust valve mechanism, means for operating the said mechanism comprising a valvular device provided with a rocking portion, means for operatively connecting the said rocking portion and valve mechanism, air conduits and mercury conduits projecting from opposite sides of the said rocking portion of the valvular device, the said air and mercury conduits being in communication at their outer ends and the said air conduits being arranged in a higher position than the mercury conduits, means for connecting the inner ends of the said mercury conduits, the said valvular device being constructed and arranged to alternately admit air to and permit it to escape from the air conduits, a body of fluid mercury in the mercury conduits, and means for supplying compressed air to the valvular device whereby the mercury is driven from one mercury conduit into the other causing the same to rock.

5. In a direct air displacement pump, the combination with a pumping chamber, of air inlet and exhaust valve mechanism, means for operating the said mechanism comprising a mercury conduit pivoted at its middle portion whereon it may rock, means for connecting the rocking mercury conduit with the said valve mechanism, a body of liquid mercury in the said conduit, air conduits connected with the outer ends of the mercury conduit, a valvular device whereby air is alternately admitted to and permitted to escape from the said air conduits, the said valvular device being connected with the said mercury conduit and operated thereby, and means for serving compressed air to the said valvular device whereby the mercury is driven from a lower into a higher portion of the said mercury conduit causing the same to rock.

In testimony whereof I affix my signature.
JOHN RIGLING.
